Fig - 4

Fig - 5

Fig - 6

FIG. 1 is a perspective view of a trap showing my new design.

FIG. 2 is a top plan view;

FIG. 3 is a left side elevational view;

FIG. 4 is a front elevational view;

FIG. 5 is a right side elevational view; and

FIG. 6 is a bottom plan view.

The broken line representation of a pipe clamp and fragmentary broken line representation of a pipe in FIG. 1 are for purposes of illustration only.

I claim:

The ornamental design for trap, as shown and described.
